CLAIM

We claim a novel design for an all vehicle cargo mat, as shown and described.

DESCRIPTION

FIG. 1 is a perspective view of the mat;

FIG. 2 is a top view of the mat;

FIG. 3 is a rear view of the mat;

FIG. 4 is a front view of the mat; and,

FIG. 5 is a side view of the mat with the opposite side being a mirror image of the first side.

A central portion of the upper surface of the mat is shown in dotted line for environmental purposes only and forms no portion of the design. The bottom surface of the mat is unadorned and forms no portion of the design.
